UNITED STATES PATENT OFFICE.

CHARLES E. BEDAUX, OF CLEVELAND, OHIO.

GAME APPARATUS.

Application filed September 8, 1921. Serial No. 499,166.

To all whom it may concern:

Be it known that I, CHARLES E. BEDAUX, a citizen of the United States, residing at Cleveland, in the county of Cuyahoga and State of Ohio, have invented new and useful Improvements in Game Apparatus, of which the following is a specification.

The present invention relates to game apparatus; and its object is to provide apparatus whereby a game simulating horse racing and the like may be played.

This object is attained by, and the invention finds preferable embodiment in, the apparatus hereinafter particularly described in the body of this specification and illustrated by the accompanying drawings, in which:—

Figure 1 is a view of the principal member of my game apparatus, shown in horizontal section on planes corresponding to line 1—1 of Figure 2;

Figure 2 is a view of the same, shown in vertical section on a plane corresponding to line 2—2 of Figure 1, the projector being shown in position ready to operate and its operating springs being omitted for the sake of clearness;

Figure 3 is a view of a portion of the same;

Figure 4 is a view in perspective of said principal member, its closure being open;

Figure 5 is a view in perspective of said member positioned on a playing board; and

Figure 6 is a view, much enlarged, of one of the playing pieces.

In the embodiment of the invention chosen for illustration by the drawings and for detailed description in the body of this specification, the principal member 1 of my game apparatus has a base 2, top and side walls 3, 4, and floor 35, forming a container 5 with an opening 6 in front which may be closed and opened by a closure, a pair of which 7, 7 are shown hingedly mounted at 8, 8 and having springs 9, 9 pressing them to the open position shown in Figures 4 and 5 and indicated in dotted lines in Figure 1. This principal member 1 has also a projector, which in the construction shown comprises a portion 10 (which in the position seen in Figure 2 completes the rear wall 4 of the container), a cross bar 11 in which is threaded the screw 12 journalled at 13 on the body of member 1, and projector-operating springs 36 pressing the portion 10 and the cross bar 11 from each other. This portion

10 has a keeper 14, which, when the portion 10 is moved backward against the pressure of the springs 36, engages and is releasably held by retaining means,—the catch 15 on the lever 16 fulcrumed at 17. The portion 60 10 is guided in its forward and backward movements by its handles 18 extending through guide slots 19 in the opposite walls of the container, which handles are grasped by hand to move the portion 10 backward into the holding engagement of the catch 15. The portion 10 and cross bar 11 are guided in their interrelative movement by the rods 20 on the portion 10 telescoping in the hollow cylinders 21 on the cross bar. The cross bar's movement is guided by the rods 22 carried by the body of member 1 and sliding in suitable guide orifices 23 in the cross bar. The 65 limit of expansion of the springs 36 is governed by turning the handle or knob 24 of the screw 12 which thus moves the cross bar 11 nearer to or further from the furthest forward position of the member 10, said position being fixed by the ends 25 of the slots 19. The closures 7, 7 are held in closed 70 position against the pressure of their springs 9, 9 by a catch 26 on the lever 27, said catch 75 engaging and holding the upper edges of the closures. This lever 27, fulcrumed at 28, is connected by a link 29 to the lever 16, so that when the lever 16 is moved by its handle portion 30 to release the keeper 14, the closures 7, 7 are released from the catch 26; but sooner than the keeper 14 of 80 the portion 10 is released from the catch 15.

Suitable playing pieces, 31, distinguishingly marked, which may assume the form of horses and riders as shown in Figure 6, are placed in the container, and the closures 7, 7 being closed, are shaken in the container as dice in a dice box. The member 1 is then placed base downward on a level surface, as in a marked position on the board 32; whereupon the handle 30 being pressed, the closures are permitted to fly open and the playing pieces are ejected from the container simultaneously and are thus projected to various positions on the board 32, such relative positions being readily estimated by the marked lines 33 which cross the board at right angles to the line of projection of the playing pieces, viz, the direction of expansion of the springs 36. The playing pieces are desirably weighted at their bases 37 so 100 105 110

that when at rest they may assume an upright position.

It will be understood that, inasmuch as the playing pieces are loosely contained in the container and are shaken when the closures are shut, their relative position on the floor of the container cannot be seen by the players. This fact, which affects the distance to which the playing pieces may be projected by the projector on the board 32, affords the element of pure chance in guessing how far the playing pieces will be projected from the container. When the handle 30 has been pressed far enough to release merely the closures 7, 7 the position of the playing pieces on the floor of the container may now be seen and the players may modify or change their guesses, because although the position of the playing pieces on the container's floor determines to some extent the probability of their being projected to a greater or less distance, still the probability in this respect may be affected by their striking each other in being expelled. The handle 30 may now be pressed further, whereupon the catch 15 will release the keeper 14 and the playing pieces will be ejected from the container.

The following method of marking the results of the game may be adopted:

If there be six players and therefore six playing pieces, and if playing piece No. 3 for instance, be projected further from the container than any other, that piece (the "winning" piece) is marked on the record of the game "5 to 1;" the playing piece (the "place" piece) projected next furthest is marked "3 to 1" and the playing piece (the "show" piece) projected next furthest is marked "2 to 1" on the record of the game, provided the player has guessed his piece to attain such position. And if any playing piece guessed to be the "place" or the "show" piece is projected further, it is to be marked

"place" or "show" piece nevertheless on the record of the game.

The invention being intended to be pointed out in the claims, is not to be limited to or by details of construction of the particular embodiment thereof illustrated by the drawings or hereinbefore described.

I claim:

1. In game apparatus; a container having an opening and a closure therefor; which when closed conceals from view the herein-after mentioned playing pieces in the container; a spring pressing the closure to open position; means for retaining the closure in closed position and for releasing the same; a projector having an operating spring; means for retaining the projector's spring in compressed position and for releasing the same; and operable in connection with and subsequently to the releasing operation of the means for retaining the closure in closed position; playing pieces adapted to be loosely contained in the container in its closure's closed position and to be ejected therefrom by the projector in the open position of its closure.

2. In game apparatus; a container having an opening and a closure therefor which when closed conceals from view the herein-after mentioned playing pieces in the container; a spring pressing the closure to open position; means for retaining the closure in closed position and for releasing the same; means for retaining the projector's spring in compressed position and for releasing the same; playing pieces adapted to be loosely contained in the container in its closure's closed position and to be ejected therefrom by the projector in the open position of its closure.

In testimony whereof I have hereunto set my hand.

CHARLES E. BEDAUX.
